UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A LANDSIDE.

SPECIFICATION forming part of Design No. 32,065, dated January 2, 1900.

Application filed December 2, 1899. Serial No. 739,053. Term of patent 14 years.

To all whom it may concern:

Be it known that I, GEORGE W. REAM, a citizen of the United States, residing at Canton, Stark county, State of Ohio, have invented and produced a new and original Design for a Landside, of which the following is a specification.

In the accompanying drawings, Figure 1 is an elevation of one side of the design embodying my invention. Fig. 2 is a plan view looking down upon the upper edge. Fig. 3 is a view of the side opposite to that shown in Fig. 1.

My invention is a new design for the landside of a plow, and the leading feature is in its outline configuration, the surfaces of the plate constituting the landside being parallel and plain.

The landside has a straight lower edge *a* terminating at the front end in a right-angled vertical wall *b*. At the rear or opposite end the landside is curved as at *c*, the upper end of the curved line merging into an inclined edge *d*, which extends at an angle to the top line *e*, this latter edge or line *e* being parallel to the bottom line *a* of the landside. From the top edge *e* the corner of the landside is cut by a line *f*, connecting the lines *e* and *b*.

I claim—

The design for a landside herein shown and described.

GEORGE W. REAM.
